UNITED STATES PATENT OFFICE.

FREDERIC N. BUSHNELL, OF PROVIDENCE, RHODE ISLAND.

STEAM-ENGINE VALVE MECHANISM.

SPECIFICATION forming part of Letters Patent No. 622,603, dated April 4, 1899.

Application filed June 23, 1898. Serial No. 684,208. (No model.)

To all whom it may concern:

Be it known that I, FREDERIC N. BUSHNELL, of Providence, in the county of Providence and State of Rhode Island, have invented 5 certain new and useful Improvements in Steam-Engine Valve Mechanism; and I do hereby declare that the following is a full, clear, and exact description thereof, reference being had to the accompanying drawings, and 10 to the letters of reference marked thereon, which form a part of this specification.

This invention refers to steam-engine valve-operating mechanism, and especially to the connection of the eccentric-rod with the 15 arm of the valve. It is fully explained and illustrated in this specification and the accompanying drawings.

Figure 1 shows a part of the valve-arm and the joint-case, taken partly in section on 20 line 1 1 in Fig. 2, with the eccentric-rod in section. Fig. 2 is a section of the joint-case and lock, taken on line 2 2, Fig. 1, looking downward. Fig 3 shows a front elevation taken to the right of Fig. 1 with the lock re- 25 moved from its position. Fig 4 shows a separate top view of the lock. Fig. 5 is a front elevation of a part of a steam-engine cylinder with the mechanism attached.

The object of the invention is to produce a 30 locking-joint to secure the eccentric-rod to the valve-arm that with an allowance for an easy oscillating motion of the rod shall be simple in construction and capable of automatically taking up all lost motion caused by 35 wear and at the same time can even when the engine is in motion be thrown in or out of connection by a single movement.

The construction is as follows: A is the arm, attached to or connected with the valve 40 G, Fig. 5. A shell or case D is chambered in from its outer end and is held rigidly fast to the arm A by means of a stud B, the round head of which is countersunk in the bottom of the chamber inside. This stud B has a nut 45 v fitted on its outer end, by means of which the case is clamped fast to the arm A, and a pin or key s is inserted from the inside to keep the case D from turning on the arm. An oval opening K is made in each side of 50 the case D to allow the eccentric-rod C, which passes through them, to have a vertical oscillating motion as the arm A swings to move

the valve. A round block S is fitted to turn easily and closely in the chamber of the case D, and a hole is made through the block that 55 agrees with the oval openings K in the case when the block S is in the chamber. The hole in the block S is made just large enough to allow the eccentric-rod C to slide in it. Two ears d d are made on the outer end of 60 the block S, between which the lock J (see Fig. 4) swings vertically on a pin a, that passes through the ears and the lock. Two recesses c c are milled in the outer side of the eccentric-rod C, and the inner end of the lock 65 J has two teeth c' c' made on it that fit into the recesses c c in the rod. The circle on which the teeth c' c' are made is struck from a point outside the center of the pin a on which the lock J swings, and when the outer 70 end of the lock moves down the teeth c' c' being on an eccentric curve will enter the recesses c c still deeper, and a weight H is put on the outer end of the lock to press the teeth up in the recesses and take up any lost motion caused by wear. 75

In operation when the eccentric-rod C is moved endwise by the eccentric the motion is conveyed through the block S and case D to the arm A by the teeth c' c' catching in the 80 recesses c c in the eccentric-rod. As the arm A swings back and forth the block turns a short distance each way in the case, the oval holes in the sides of the case allowing the necessary motion to the eccentric-rod. When 85 it is required to disconnect the rod so it will not move the arm, the handle of the lock J, with the weight H, is turned up and the teeth c' c' will be turned down out of the recesses c c in the rod and it will be free to slide in 90 the hole in the block S without moving any of the parts, and by dropping the handle and weight the connection is again made. As before stated, the weight H holds the teeth up close in the recesses, and if any wear takes 95 place it forces the teeth a little farther up, and owing to their eccentricity they advance a little deeper into the recesses and take up all the wear, and thus prevent all lost motion. A spring may be substituted for the weight 100 H, if preferred.

In some situations it may be preferred to make the stud B and block S in one piece and made rigid on the arm and have the case

D loose on the block to carry the lock held in ears made on it. The operation of the lock would be the same if made in either way.

Having thus described my improvements, 5 I claim as my invention and desire to secure by Letters Patent—

1. In an operating connection for an engine valve-gear, the combination of an eccentric-rod a case rigidly secured to the swinging 10 arm that operates the valve-gear, a block fitted to turn in said case and having a hole in it to receive the eccentric-rod, ears made on said block, a cam held between said ears to swing transversely to the line of said rod, a 15 tapering transverse recess made in said eccentric-rod to receive a tapering tooth on the inner side of the cam, an arm on the outside of the cam, a weight on the outer end of the arm to hold the cam in or out of engagement 20 with the rod, substantially as described.

2. In a connection for an engine valve-gear,

the combination of an eccentric-rod, a case with holes in its sides connected to the swinging arm that operates the valve-gear, a block fitted to turn in said case having a hole in it 25 to register with the holes in the case, through which said eccentric-rod passes to hold the two together, a cam having one or more tapering teeth, held in ears to swing transversely to the line of said eccentric-rod, one 30 or more tapering transverse recesses made in said eccentric-rod to receive the teeth of said cam, a weight on said cam to hold it in or out of engagement with the rod and to cause the cam to take up wear and prevent lost motion, substantially as described.

In testimony whereof I have hereunto set my hand this 11th day of June, A. D. 1898.

FREDERIC N. BUSHNELL.

In presence of—

BENJ. ARNOLD,
M. E. CLEVELAND.
